ABSTRACT OF THE DISCLOSURE

A machine for automatically faceting gem stones which enables a complete ring of facets to be formed on a stone automatically, the machine having a control system for automatically polishing each facet to the same depth and automatically indexing the stone to different facet forming positions between each polishing operation.

This application is a continuation-in-part of my earlier application Ser. No. 690,915, filed Dec. 15, 1967, and now Pat. No. 3,520,088, dated July 14, 1970.

This invention relates to gem stone shaping to produce a product ready for sale to the public.

In this specification, the words "gem stone" include such elements as natural or artificial rubies, emeralds, semi-precious stones, diamonds, hard glasses and the like.

In a common form of treatment say, a diamond, the uncut stone is firstly equipped with a girdle zone which distinguishes the top of the stone from the base area. Thereafter the stone is gripped in a pot for subsequent attachment to a dop which in turn is anchored to a tang. The tang is then used as a means of maintaining the gem in contact with a polishing wheel which is usually made of cast iron impregnated with diamond particles. When a facet is developed in the gem, the next facet can only be started by changing the location of the stone relative to the wheel. It is customary practice for the polishing of a facet to be accompanied by a zooting motion of the gem over the wheel surface. This means that the tang is given a radial oscillating movement over the wheel surface.

It is known in the diamond polishing art, that in polishing any particular stone, once the girdle zone and table have been established, the various facets must all be polished in more or less precise positions. The direction however, in which each facet is polished relative to the polishing wheel varies from facet to facet depending on the grain structure of the stone. Once the correct polishing position for one facet has been established it is possible to predict reasonably reliably what the polishing directions for the remaining facets should be, such directions normally being in multiples of 45° from the polishing direction of the first facet. For a machine which aims at automatically polishing substantially all the required number of facets onto a stone, it must therefore be capable of positioning the stone in numerous polishing directions for the various facets.

An object of the present invention is to provide an automatic gem stone polishing machine which provides a facility for polishing a series of facets in different polishing directions based on the prediction that the various facets can be polished in directions bearing definite angular relationships to the polishing direction of the first facet.

Another object of the invention is to provide the machine with a manual override capability because in certain circumstances the prediction of polishing directions for particular facets may not work out and the opera-

2

tor must then be able to change the polishing direction manually.

To provide a multi-position capability of polishing direction the present machine employs an electric motor to 5 rotate the gem stone holding chuck about an orbital axis relative to the polishing wheel as required between facetting operations and means for stopping the electric motor in each case after it has rotated through a certain angle based on the prediction of correct polishing direction required for the next facet. The machine is capable of being programmed so that the degree of rotation of the motor between succeeding facets is variable dependent on the prediction of polishing direction required for the succeeding facets. In practice, the operator would at commencement of polishing set a number of switches which programmes the motor to rotate through various degrees as and if between succeeding facets to establish the pattern of direction changes.

The invention accordingly consists in apparatus for automatically developing a plurality of facets on a gem stone comprising a tang, a chuck mounted on the tang adapted to carry a gem stone or a gem stone in a holder with the stone axis inclined to the tang, the chuck being capable of rotational motion about the stone axis and orbital motion about another axis substantially perpendicular to the tang, means for lowering the tang towards a polishing surface, means for lifting the tang away from the polishing surface, first indexing means for rotating the chuck in facetting steps about the stone axis, second indexing means 25 independent of the first indexing means for orbiting the chuck about said another axis to alter the polishing direction, the second indexing means comprising electric motor means, and automatic control means for repeatedly operating the lifting and lowering means and the first 30 and second indexing means to successively develop a plurality of facets on the stone, the control means including means for automatically operating the tang lifting means when each facet has been polished to the same predetermined depth, means for automatically operating the first 35 indexing means between each successive facetting operation and means for preselecting a sequence of positions for the chuck about said another axis for succeeding facetting operations dependent on the polishing directions required by the succeeding facets, and for actuating the 40 motor means accordingly between at least some facet polishing operations to establish a programmed polishing direction control.

In a preferred form of the invention, the apparatus includes means for continuously reciprocating the chuck 50 over the polishing surface during polishing to effect a smoothing action conveniently in the form of automatically reversing motor means for reciprocating the tang in its longitudinal direction. This reciprocating motion of the tang may be accompanied by reciprocatory orbital motion of the chuck about said another axis.

To effect lifting of the tang for terminating polishing when each facet has received the same predetermined depth of polishing, the control means may include means establishing an electrical conducting path by contact of 55 the chuck or stone holder with the polishing surface and tang lifting means operative in response to the establishment of said conducting path.

An auxiliary control arrangement may be provided at 60 a strategic point for an operator so that movement of the stone about the two axes may be adjusted to suit requirements. Preferably, the control arrangement includes a switch bank, the bank allowing any selected zone of the 65 stone to be worked through rotation of the chuck about the stone axis and which allows for changes to be made in the direction of polishing by moving the gem in the orbit about 70 said another axis. The auxiliary control arrangement may

be subordinate to the control means which automatically moves the stone around its axis in a step-by-step movement, each step corresponding to a particular facet on the stone.

Preferably, movement of the chuck can also be accomplished by the operator through the switch bank or the like independently of the operation of the control means.

The lowering of the chuck is an automatic step following adjustments in the angular setting of the stone relative to the abrading surface and in regard to the means for lowering the chuck a cushioning arrangement such as a dashpot control system may be employed to ensure that the stone makes a gentle contact with the surface.

An electric motor may be employed to oscillate the tang over the grinding surface. Preferably, the arrangement is one in which a carriage is oscillated in or on a track and the tang engages a carriage element, tongue and groove fashion, so that the tang may be removed to inspect the progress made on the gem without having to stop the device.

In order to illustrate the invention, an example is described hereunder with reference to the accompanying drawings, in which FIG. 1 is a composite view of a polishing machine showing the mechanical components in perspective and an automatic control system therefor in block diagram form, and FIG. 2 is a fragmentary perspective view of one form of chuck indexing mechanism which can be used in the machine.

A tang 1 includes a metal bar 2 which at one end is equipped with a claw arrangement 3 for engaging over a bar 4 on carriage 5 and at the other end provides a pivot 6 perpendicular to the tang for a depending chuck. The chuck 7 is capable of moving in an orbit about the axis defined by the pivot 6 through the agency of an electric motor 8 anchored to the tang, the axis being perpendicular to a grinding wheel 9. In addition, the chuck is capable of rotating about a further axis 10 which is inclined to the surface of a polishing, abrading or grinding wheel or disc located beneath the chuck. The inclined axis passes through the centre of a gem held by a holder in the chuck and the purpose of rotating the leading end of the chuck about the inclined axis is to present different parts of the gem to the abrading surface for the production of different facets on the stone. A gem holder of the type described in South African patent application No. 66/0624 may be used to hold a stone in the chuck. Thus, when the stone first engages the abrading surface a first facet is developed. If now the chuck is turned through, say, 20 degrees about the stone axis, then the apparatus will now ensure the development of a second facet on the stone, and so the process proceeds until a whole ring of facets is produced.

Also, the chuck is mounted on a pivoted bracket 11 to provide means for adjusting the inclination of the chuck, i.e. the inclination of the stone axis to the tang so that different rings of facets requiring different polishing angles can be developed.

The carriage 5 is mounted on a base 12 through rollers 13 guided in tracks 14, and an automatically reversing double acting hydraulic piston and cylinder 15 is connected to the carriage for reciprocating the latter across base 12 to effect continuous reciprocation of the stone across the wheel during polishing. For example, when the piston and cylinder is operating, a trip can be arranged to be operated by the piston at each end of its stroke to reverse the cylinder valving arrangements. A single acting pneumatic piston and cylinder assembly 16 anchored to the base 12 is provided for lifting the tang between faceting operations as will be described.

The arm 2 of the tang has a downwardly depending follower 17 adapted to press on a dashpot assembly 18 as the tang is being lowered towards the wheel to cushion the downward motion of the tang, the arrangement being such that a floating member 17a of the dashpot is depressed by the tang as the tang is lowered and this member rises when the tang is lifted.

It has been established in diamond polishing that particular facets can usually be polished in directions bearing an angular relationship. For example, for a diamond which is to have eight facets with adjacent facets numbered in sequence F1 . . . F8, then facets F2 to F8 can each be polished in a particular direction relative to a direction suitable for polishing facet F1. Accordingly, having established this polishing direction for facet F1, the remaining facets can each be polished at a particular orbital position of the chuck about axis 6 relative to the orbital position about this axis for polishing facet F1. Therefore, the machine can be programmed to correlate the position of the chuck about its own axis 10 with its position about the vertical axis 6 between each polishing operation. This aspect of the invention, and the control system as a whole, will be described with reference to the working cycle of the machine.

Assuming a ring of eight facets F1 to F8 is to be developed on a diamond, then section B of a control unit 1 C.U., which section controls the chuck position, will be programmed to index the chuck in steps of 45 degrees about axis 10 between each facet polishing operation to develop adjacent facets successively, and to index the chuck about vertical axis 6 in steps dependent on the polishing direction required for the successive facets.

To commence polishing, an operator positions a stone in a holder in the chuck and sets bracket 11 at an inclination suitable for the polishing angle required for the ring of eight facets. The carriage 5 is set reciprocating through an actuating mechanism D of the control units which effects automatic and continuous reciprocatory operation of the piston and cylinder 15. The tang is gently lowered onto the wheel by pressing on dashpot 7, and then a suitable polishing direction is established manually for the first facet and the orbital position of the chuck relative to vertical axis 6 is manually set accordingly. Then, the automatic control sections A, B and C can be operated because the polishing directions for the remaining facets will all have fixed angular relationships to that of the original facet which will be established by the control system.

Having actuated sections A, B and C of the control unit, automatic operation proceeds as follows:

Polishing of the first facet continues until the gem holder contacts the polishing wheel. The holder has an electrical connection a through the chuck to section A of the control system, and the wheel also has a connection b to section A. Thus, when the holder contacts the wheel, a circuit is established which through a suitable relay and a circuit C signals piston and cylinder 16 to rise, to lift the tang off the wheel.

When the tang has lifted, another relay, which could be operated directly from piston 16, activates section B of the control system to index the chuck about axis 10 through 45 degrees for polishing the succeeding facet, and to index the chuck about axis 6 by an amount suitable for establishing the correct polishing direction for this succeeding facet. Should a pair of succeeding facets be capable of being polished in the same direction or if the chuck is indexed about axis 10 in steps of more than one facet then the orbital position of the chuck would not be altered between succeeding polishing operations. This would be taken care of by suitable programming of section B of the control system. Any known form of automatic programmer can be used.

To effect accurate indexing of the chuck about axes 6 and 10, the programmer can be operated on a time base with controls d and e leading respectively to constant speed motors 8 and 20 adapted through the programmer to rotate the chuck about the respective axes for a set time. To improve accuracy the motors can be coupled to the chuck through speed reduction means.

When section B has completed the indexing movements

of the chuck, it operates a further relay actuating section C of the control unit which signals cylinder 16 to lower and thus again bring the tang down onto the wheel to polish the next facet. A relay operated by piston 16 can then again activate section A of the control unit so that when the holder again touches the wheel, signifying the completion of polishing of the second facet, the tang will again lift. Thus, the process is automatically repeated for all eight facets.

A counting mechanism can be included in the control unit to stop the machine when all facets have been polished and/or to actuate a visible or audible signal on completion of all eight facets to alert the operator.

One form of indexing arrangement for moving the chuck about axis 6 in programmed steps dependent on the polishing direction required for succeeding facets, is illustrated in FIG. 2. The output shaft of motor 8 is coupled to a shaft 22 whose lower end is attached to the chuck carriage 11a (FIG. 1) the shaft being carried in bearings 23 in a casing 21. The shaft carries a slip ring 25 insulated from the shaft and having a wiping contactor 26 attached thereto adapted as the shaft rotates, to sweep over a segmented commutator 30 fixed in the casing. Each segment of commutator 30 has an electrical connection with a switch in a switch bank associated with the machine control unit (only one such connection being shown in FIG. 2) a stationary slip ring contactor 27 is connected to one leg of a power supply suitable for operating a relay 31 and the circuit being completed by a connection from the switches to the relay.

The relay controls motor 8 through a separate circuit so that the relay in its normally off condition causes the motor to rotate and in its on condition stops the motor.

In use, after the polishing direction of the first facet has been established, the operator activates those switches associated with the particular commutator segments required to stop the motor in the appropriate positions to establish the correct polishing directions for the succeeding facets.

During polishing of a facet contactor 26 is in contact with a segment of the commutator which has been activated by its associated switch, causing current to flow from contact 27 to relay 37 thereby activating the relay so that the motor is stopped. When polishing of the facet is terminated and the tank is lifted, a time impulse from the control unit de-activates relay 31 causing the motor

8 to rotate until the contactor 26 contacts the next commutator segment which has been activated by its associated switch again causing current to flow from contactor 27 to relay 31 to stop the motor in the required position for establishing the programmed polishing direction for the next facet.

In place of the manually operable switch bank, an automatic selector device could be used to activate the required commutator segments.

I claim:

1. Apparatus for automatically developing a plurality of facets on a gem stone comprising a tank, a chuck mounted on the tank adapted to carry a gem stone or a gem stone in a holder with the stone axis inclined to the tang, the chuck being capable of rotational motion about the stone axis and orbital motion about another axis substantially perpendicular to the tang, means for lowering the tang towards a polishing surface, means for lifting the tang away from the polishing surface, first indexing means for rotating the chuck in faceting steps about the stone axis, second indexing means independent of the first indexing means for orbiting the chuck about said another axis to alter the polishing direction, the second indexing means comprising electric motor means, and automatic control means for repeatedly operating the lifting and lowering means and the first and second indexing means to successively develop a plurality of facets on the stone, the control means including means for automatically operating the tang lifting means when each facet has been polished to the same predetermined depth, means for automatically operating the first indexing means between each successive faceting operation and means for preselecting a sequence of positions for the chuck about said another axis for succeeding faceting operations dependent on the polishing directions required by the succeeding facets, and for actuating the motor means accordingly between at least some facet polishing operations to establish a programmed polishing direction control.
2. The apparatus of claim 1 in which said last named means comprises a slip ring and segmented commutator device and means for activating selected ones of the commutator segments to preselect said sequence of positions for the chuck by stopping the motor means when a contactor of the slip ring contacts one of said activated segments.
3. The apparatus of claim 1 including means for continuously reciprocating the chuck over the polishing surface during polishing to effect a smoothing action.
4. The apparatus of claim 3 wherein the means for continuously reciprocating the chuck comprises automatically reversing motor means for reciprocating the tang in its longitudinal direction.
5. The apparatus of claim 1 wherein the control means includes means establishing an electrical conducting path by contact of the chuck or stone holder with the polishing surface and means adapted to operate the tang lifting means in response to the establishment of said conducting path to terminate the polishing of each facet at the same predetermined depth.
